UNITED STATES PATENT OFFICE.

JOSEF METTLER, OF ZUG, SWITZERLAND, ASSIGNOR TO LANDIS & GYR A.-G., OF ZUG, SWITZERLAND.

TIME SWITCH.

Application filed September 6, 1922. Serial No. 586,496.

To all whom it may concern:

Be it known that I, JOSEF METTLER, a citizen of the Swiss Confederation, residing at Zug, in the Canton of Zug, Switzerland, have made a new and useful invention relating to Time Switches, of which the following is a full, clear, and exact description.

The purpose of the present invention is to overcome the disadvantages of such time switches in which the entire force necessary for the switching in and out is taken from the clockwork driving the dial at the moment when the switching takes place. This is very disadvantageous, since the regular going of the clockwork is seriously affected. Arrangements by means of which the necessary mechanical force for the operation of the switch may be stored during the time that the switch runs light have already been suggested in order to get over this difficulty. With such arrangements, however, the storage of the force takes place only intermittently: that is to say, the clockwork is only required to store force from time to time, and thus the unequal loading of the clockwork is not entirely done away with. Also the switching times are in this case dependent on the arrangement of the means for the storage of the force, and a certain time is required to effect the necessary storage i. e. it is not possible to choose the switching times at will, nor as close to one another as may be desired. The same applies, to a large extent, to arrangements in which the switch is required to pass through the final switching position without stopping, should the switchings "on" and "off" coincide, and in which a spring is employed for the storage of the necessary energy. This spring is fixed at both ends and must be somewhat weak, so as to allow of a 360° rotation of the dial without fear of the spring breaking. As a result the operation becomes unreliable if two switching operations follow one another closely, since the force stored is very small, and may be insufficient to operate the switch drum used with this arrangement.

The present invention relates solely to a time-switch of the type in which the necessary force for the operation of the switching mechanism is stored up during the period when the clockwork of the switch runs light; this time-switch has, however, certain advantages in comparison with other known time-switches.

Fig. 1 of the accompanying drawing shows a front elevation of one form of the invention, some of the parts at the top left hand corner of the drawing being shown in section. Fig. 2 is a side-elevation, one part of which is cut along the line II—II of Fig. 1. Figure 3 is a detail side elevation.

Figure 4 is a detail plan partly in section. The dial 1, which may be marked off in twenty-four hours, is fitted with control levers 2. The dial is fitted with a sleeve 3 by means of which it is mounted on the fixed arbor 3', a toothed wheel 4 being rigidly mounted on the sleeve 3. This toothed wheel 4 is driven from the clockwork 5' through the toothed wheel 5 and meshes with a second toothed wheel 6. The toothed wheel 6 is loosely mounted on a spindle 7, on which a hub 8, and a toothed wheel 10 forming part of a multiple armed ratchet member 9 are rigidly mounted. The toothed wheel 10 gears with a toothed wheel 11 with which a rod 13 is connected by means of a crank pin 12. The rod 13 is connected to the lever 14 which is carried in bearings mounted on an insulating plate 15, and acts on the contact springs 16. These contact springs 16, together with the solid contacts 17, form the switching mechanism of the time-switch.

One end of the spiral spring 18 is bent up and attached to the toothed wheel 6. This spring 18 is coiled round the spindle 7, with a sufficiency of play between it and the spindle, and the other end of the spring is tightly coiled about a cylindrical portion of the hub 8. A conical part of the hub 8, which forms a continuation of the cylindrical part leads the spiral spring 18 on to the cylindrical part and prevents the coils of the spring from suddenly slipping or binding on the hub 8. The spindles 19 and 20 form locking and tripping members respectively, and are coupled together by means of the toothed segments 21. On each of these spindles 19 and 20 is cut a flat 22, these flats lying in the plane of the ratchet member 9 and working in conjunction with same. The spindle 19 is provided with striker arms 23 and 24.

As has already been mentioned, the dial 1 is put in motion by the clockwork 5' of the time switch through the toothed wheel 5, and the scale marked on same passes under a fixed pointer 1' mounted on the fixed

arbor 3'. As a result the toothed wheel 6 is turned and the spiral spring 18 tends to turn the spindle 7 with it. Since, however, one arm of the ratchet member now rests 5 against the circumference of one of the spindles 19, 20,—against spindle 19 for example (see Fig. 1)—the turning of the spindle 7 is prevented, and the spring 18 becomes more and more tightly wound, until, finally, 10 the tension overcomes the friction between the spring and the hub 8 and the spring slips on the latter. During this stage the switch mechanism 16, 17 is in the "on" position. In the course of the rotation of the 15 dial plate 1 the next control lever comes into contact with the striker arm 24 by means of the operating pin 25, and the striker arm, and with it the spindle 19, is thus turned. As the spindle 19 turns, the 20 arm of the ratchet member 9 slips off the circumference of the spindle 19 and, under the action of the spiral spring, passes by the flat 22 on the spindle. In the meantime the spindle 20 whose flat 22 before 25 commencement of the rotation lay in such a position as to allow the arms of the ratchet member 9 to pass freely, has now been turned by means of the geared segments 21, so that its circumference now lies in the 30 path of the arms of the ratchet member 9, so that the arm which has been released by the spindle 19 is now arrested by the spindle 20, and the rotation of the spindle 7 is limited to a partial turn. During this rotation of the spindle 7 the rod 13 moves upwards, thus bringing the switch mechanism 16, 17 into opposite position, i. e. into its 35 "off" position.

Upon further rotation of the dial, during 40 which the spring 18 is once more wound up, the next control lever 2 comes into contact with the striker arms 23 by means of the operating pin 25, and thereby returns the spindles 19, 20 to their original positions, 45 whereupon the spindle 20 releases the arrested arm of the ratchet member 9, and the spindle 19 arrests the following arm.

Instead of the multiple arm ratchet member and two tripping spindles the arrangement shown in Fig. 3 might be employed, whereby a one armed locking member 9' is mounted on a spindle 7' to which is attached the moving part 26 of the switch mechanism 26, 30 of the time-switch. The spring 50 18' resembles in its winding and arrangement the spring 18 described in the first form of the invention. The spindle 27 carries striker arms 23' and 24' and is provided with two flats 28 and 29. The end 55 of the locking member 9' is bent and works in conjunction with the flats 28 and 29, and the locking member 9' is arrested by the circumference of the spindle 27 and is released alternately by the flats 28 and 29. The 60 65 striker arms 23' and 24' work with the bent

arms of the control levers 2' mounted on the dial. A pin 32 passing through between the striker arms 23' and 24' forms a stop which limits the rotation of the spindle 27 in either direction. 70

In all the forms of the invention hereinbefore described the spiral spring 18 (respectively 18') is driven by the clockwork in the opposite sense to that in which it is coiled, since, otherwise, it might bind on the hub 8 (respectively 8') and break. In the form of the invention shown in Fig. 4 the friction end of the spiral spring 18'' is arranged in a sleeve 31, which for the reason mentioned has a conical and a cylindrical internal surface as bearing surface for the spiral spring 18''. The spiral spring 18'' is driven by the clockwork (not shown in the illustration) in the sense in which the spring is coiled. 75 80 85

In all three forms of the invention a switch drum could be employed as switching device.

Time switches in accordance with the invention have the advantage that the switching operations may be set for any desired time, and may be arranged to follow one another as closely as may be desired, there being always sufficient force to ensure a reliable operation of the switch. 90 95

What I claim is:—

1. A time switch having means whereby the necessary force for the operation of the switching mechanism is stored during the time that the clockwork which actuates the release of the mechanism operating the switch is running light, these means consisting of a spring and a friction coupling connecting the clockwork with a tripping mechanism controlling the switch mechanism. 100 105

2. A time switch with a spring and a friction coupling, whereby the spring serves to operate the switching mechanism and is positively coupled with the clockwork at one end, whilst at the other end it slips on a member with which it forms the friction coupling, the said member being positively coupled to a tripping mechanism which controls the switching mechanism of the time switch. 110 115

3. A time switch with a spring and a friction coupling, the spring being spiral in form and serving to operate the switching mechanism, the said spring being positively coupled at one end with the clockwork and slipping at the other end on a member together with which the said spring forms the friction coupling, the above mentioned member being positively coupled to a tripping mechanism which controls the switching mechanism of the time switch. 120 125

4. A time switch with a spiral spring connected at one end with the clockwork of 130

the time switch, and with a friction coupling formed by the slipping of the other end of the spring on a member, the said member having a cylindrical and a conical bearing surface for the spring and being positively connected with a tripping mechanism which controls the switching mechanism of the time switch.

5. A time switch with a spiral spring connected at one end with the clockwork of the time-switch, and with a friction coupling formed by the slipping of the other end of the spring on a member, this member being rigidly mounted, together with 10 one part of a locking and tripping gear, on a spindle, a further part of the locking and tripping gear being provided with striker arms working in conjunction with operating pins on the dial of the time switch.

6. A time switch with a spiral spring connected at one end to the clockwork of the time-switch and with a friction coupling formed by the slipping of the other 15 end of the spring on a member, the said member being rigidly mounted, together with one part of a locking and tripping gear, on a spindle, whereby an arm forming part of the locking and tripping gear 20 works in conjunction with a flat on the spindle, there being striker arms connected to this spindle, these arms working in conjunction with operating pins on the dial of the time-switch.

35. 7. A time-switch with a spiral spring connected at one end to the clockwork of the time switch, and with a friction coupling formed by the slipping of the other end of the spring on a hub, the said hub having a 40 cylindrical and a conical bearing surface for the spring and being rigidly mounted on a spindle on which is also rigidly mounted one member of a tripping mechanism controlling the switching mechanism of the 45 time-switch.

8. A time switch with a spiral spring connected at one end to the clockwork of the time-switch and with a friction coupling formed by the slipping of the other end of 50 the spring on a hub, this hub being rigidly mounted on a spindle together with a multiple arm member of a tripping gear controlling the switching mechanism of the time-switch, whereby the said multiple arm 55 member works in conjunction with two spin-

dles, each of which is provided with a flat, these spindles forming locking and tripping members of the tripping gear and being so arranged in connection with one another that one of them always comes into its locking position before the other has reached its tripping position, whereby one of the aforesaid spindles carries striker arms which work in conjunction with operating pins on the dial of the time switch.

9. A time-switch with a spiral spring connected at one end to the clockwork of the time switch, and with a friction coupling formed by the slipping of the other end of the spring on a hub, the said hub being 60 rigidly mounted on a spindle together with a multiple arm member of a tripping gear controlling the switching mechanism of the time-switch, the said multiple arm member working together with two spindles, 65 each of which has a flat and which together form a locking and tripping gear, being so coupled together by means of toothed segments that one of them always comes into its locking position before the other reaches 70 its tripping position, whereby one of the aforesaid spindles carries striker arms which work in conjunction with operating pins on the dial of the time-switch.

10. A time-switch with a spring and a friction coupling, these parts serving to connect the clockwork of the time switch with a tripping gear controlling the switching mechanism of the time-switch, whereby the 80 said switching mechanism is in the form of a 85 knife-switch connected by means of a connecting-rod and toothed wheels to a multiple arm member, this member being mounted on a spindle on which the friction coupling acts and working in conjunction with two 90 spindles each of which has a flat, these spindles forming locking and tripping members of the tripping gear, and being so coupled together that one of them always 95 comes into its locking position before the other reaches its tripping position, whereby 100 one of the said spindles carries striker arms which work in conjunction with operating pins on the dial of the time-switch.

In witness whereof I affix my signature.

JOSEF METTLER.
